UNITED STATES PATENT OFFICE.

CLARENCE WARNER, OF DAYTON, OHIO, ASSIGNOR TO DELCO-LIGHT COMPANY, OF DAYTON, OHIO, A CORPORATION OF DELAWARE.

PUMPING APPARATUS.

Application filed September 4, 1923. Serial No. 660,723.

To all whom it may concern:

Be it known that I, CLARENCE WARNER, a citizen of the United States of America, residing at Dayton, county of Montgomery, 5 and State of Ohio, have invented certain new and useful Improvements in Pumping Apparatus, of which the following is a full, clear, and exact description.

This invention relates to pumping systems which include a pressure tank in which water is stored under pressure, so that a quantity of water may be used before it is necessary to operate the pump to supply the demand. 10 More particularly, the present invention relates to devices of the type described and illustrated in the co-pending application of Buvinger, Warner and Smith, Serial No. 628,799, filed March 30, 1923, which includes an air charger for providing a storage tank with air under pressure without requiring the use of an auxiliary air pump, and without discontinuing the water supply, the water pump itself being used as 15 the source of pressure supply for causing air to be forced into the storage tank under pressure.

It is an object of the present invention to provide an air charger apparatus which 20 will be durable and reliable, and which will tend toward compactness and reduction of the number of parts.

In the present invention, there is provided, a main duct connecting a source of water supply with a water pressure storage tank and a duct by-passing a portion of the main duct. The by-pass duct is controlled so that air is permitted to accumulate therein and when it is desirable to force air 25 into the storage tank, the by-pass duct is placed in parallel with the main duct whereby some of the water, flowing from the source of supply to the tank, will flow through the by-pass duct and force the air accumulated therein into the tank. One of the objects of the present invention is to cause the air from the by-pass duct to be readily forced into the tank. One manner of accomplishing this object is to restrict the flow of water through that portion of the main duct which is by-passed by 30 said by-pass duct whereby a large portion of the water flowing to the tank will flow through the by-pass duct.

Other and further objects and advantages 55 of the present invention will be apparent from the following description of a preferred embodiment thereof, reference being made to the accompanying drawings.

In the drawings: 60 Fig. 1 is a view in elevation of a water system embodying the present invention.

Fig. 2 is a top plan view thereof.

Fig. 3 is a fragmentary view, partly in 65 section, showing the auxiliary tank open to atmosphere and drain, but closed to the water supply.

Fig. 4 is a sectional view showing the auxiliary tank open to the water supply but 70 closed to atmosphere and drain.

Fig. 5 is a view of the restricting means in open position.

Fig. 6 is a view of the same in closed 75 position.

Referring to the drawings, a pump 20 is connected with a source of water supply by pipe 21 and with an air charger unit, designated as a whole by numeral 25 by pipe 22. The water and air outlet connections between the air charger 25 and a storage tank 100 are provided by piping 26. The tank 100 is provided with a sight glass 101 for indicating the water level in the tank 100. The tank 100 is connected with a water distribution system (not shown) by a pipe 102. Any suitable pressure operated switch may be employed for stopping the pump when the pressure within tank 100 reaches a predetermined value. 85

The air charger 25 includes a tank 27 adapted to be rotated, as indicated by dotted lines in Fig. 2, and within which air for charging the pressure tank 100 can be collected. Valve member 28 is secured to the outer surface of tank 27 and is provided with a central passage 29 which registers with an opening in the wall of the tank 27, and also passages 30 and 31 set at substantially 90 degrees with respect to one another, which are adapted to register with openings 32 and 33 respectively in the tank 27. A valve member 34 is secured to the outer surface of tank 27 directly opposite valve member 28, and is provided with a central passage 35 registering with an opening in the tank 27, and also passages 36 and 37, set at substantially 90 degrees with 100 105

respect to one another, which are adapted to register with openings 38 and 39 respectively in the tank 27. A pipe 40 which extends through tank 27 connects passages 29 and 35 and forms a portion of the main duct or passage between the pump and tank. Secured to the end of pipe 22 is a valve body 41 provided with a chamber 42 in alignment with the pipe 22, and with passages 43 and 44 set at substantially 180 degrees. Valve body 41 is adapted to receive valve member 28 and provides a seat therefor. When the tank 27 is in the position shown in Fig. 3, passages 30 and 44 register to connect the tank 27 with drain, and the passage 31 does not register with the passage 43. When the tank 27 is in the position shown in Fig. 4, passages 31 and 43 register thus connecting the tank 27 with the passage 42, and passage 30 does not register with passage 44 so that water cannot escape from the tank 27 through pipe 45. A check valve 46 is threaded into the valve body 41 for preventing water flowing back from chamber 42 into pipe 22. Drain 45 may lead back to the source of water supply or to a waste sewer.

A valve body 50 is attached to piping 26 and provides a seat for valve member 34. Valve body 50 is provided with a chamber 51, in alignment with pipe 26, and with passages 52 and 53 set at substantially 180 degrees. When tank 27 is in the normal position shown in Fig. 3, passages 31 and 37 are closed, and passages 36 and 53 and pipe 55 connect tank 27 with an air inlet controlled by check valve 54. Supporting arms 60 extend from opposite sides of the valve bodies 41 and 50, and in the present disclosure are disposed at substantially 45 degrees with respect to the plane of pipes 26 and 22. The outer ends of these arms 60 are connected by bolts 61 which pass therethrough. Springs 62 which surround the lower ends of these bolts 61 and bear against the arms 60 carried by valve body 41, and the washers 63 are held in position by nuts 64 threaded on bolts 61. The springs 62 tend to maintain the valve members 28 and 34 seated within the valve bodies 41 and 50, respectively, when the tank 27 is rotated. Bolts 61 limit the movement of tank 27 to substantially 90 degrees, from the position shown in Figs. 1 and 2. Air inlet valve 54 is connected with drain pipe 45 by a flexible tube 65 for permitting the valve members 28 and 34 to seat properly in the valve bodies 41 and 50 respectively, when the tank 27 is rotated. This pipe 65 also serves as a vent for drain 45, whereby the tank 27 may be more quickly drained of water.

The means for restricting the flow of water through passage 42, pipe 40, and passages 51 during the air charging operation

comprises a rod 66 suspended from the upper wall of valve body 50 centrally of passage 35, with a pin 67 passing therethrough adjacent the lower end of the rod. Substantially semi-cylindrical shaped restricting members 68 and 69 which fit over the top of passage 35 are held down by a headed pin 70 carried by valve member 34 and are held in contact with the shank of pin 70 by a spring 71 the opposite ends of which are secured to said restricting members. Members 68 and 69 are provided with notches 72 and 73 respectively. It will be apparent that when the valve member 34 is in the normal position shown in Figs 3 and 5 restricting members 68 and 69 will be spread apart by the engagement of pin 67 with the notches 72 and 73, thereby permitting a large amount of water to flow through passage 35 to the tank 100. However, when the valve member 34 is moved to the position shown in Figs. 4 and 6 by rotation of the tank 27, the pin 67 will no longer engage the notches 72 and 73, and the restricting members 68 and 69 will be drawn toward each other by the spring 71, thereby restricting the flow of water through passage 35 whereby a large portion of the water flows through tank 27.

The operation of the air charger will be as follows:

With the air charger in its normal position, as shown in Fig. 3, the tank 27 will be filled with air, being open to atmosphere through air valve 54, pipe 55, passage 53, passage 38 and open to drain through passage 30, passages 44 and 45. Water will flow from the pump 20, through the main duct including pipe 22, valve 46, chamber 42, pipe 40, chamber 51, piping 26 into the storage tank 100. The restricting means will be in the position shown in Fig. 5, in which position the maximum amount of water is flowing through passage 35.

The water level sight glass 101 on the tank 100 will indicate the amount of air contained in the tank 100. When the water disappears entirely from the glass 101, it is an indication that water should be pumped into tank 100; and, when the glass 101 is entirely filled with water, this is an indication that it is necessary to operate the air charger in order to maintain the necessary amount of air for pressure storage in the tank 100.

Assume that the glass 101 is entirely filled with water, thus indicating that the air charger should be operated to force air into the tank 100, and assume that the tank 27 is filled with air. The tank 27 is rotated in a clockwise direction to the dotted line position as viewed in Fig. 2, until its movement is stopped by contact with bolts 61, at which time the tank 27 will have rotated substantially 90 degrees. This rotation of the tank 27 rotates the valve members 28 and 34,

thereby closing the tank 27 to atmosphere and to drain, but opening it to the pump 20 and tank 100. Water will then flow from pump 20, through pipe 22, valve 46, chamber 42, passage 43, passage 31 into tank 27 and out through passage 37, passage 52, chamber 51, piping 26 into the tank 100, passages 43, 31, tank 27, passages 37 and 52 providing a duct which by-passes that portion of the main duct including passage 29, pipe 40 and passage 35. Thus the air within the tank 27 will be forced into the tank 100. However, the restricting means will be in the position shown in Fig. 6, and therefore only a small amount of water will flow through pipe 40 and passage 35 into the tank 100. When the pressure in the system reaches a predetermined value, the operation of the pump 20 will be discontinued by action of the pressure operated switch heretofore mentioned.

The tank 27 may then be returned to the position shown in Fig. 3 to permit the tank to drain and be filled with air ready for the next air charging operation, and for permitting the maximum amount of water to flow through passage 35.

While the form of mechanism herein shown and described constitutes a preferred embodiment of one form of the invention, it is to be understood that other forms might be adopted and various changes and alterations made in the shape, size, and proportion of the elements therein without departing from the spirit and scope of the invention.

What is claimed is as follows:

1. In a water system, the combination with a pump and a pressure storage tank; of a main passage connecting the pump and storage tank; an auxiliary tank; and means controlled by movement of the auxiliary tank for introducing air into the auxiliary tank and for causing air to be forced from the auxiliary tank into the storage tank.

2. In a water system, the combination with a pump and a pressure storage tank; of a main passage connecting the pump and storage tank; an auxiliary tank; and means controlled by movement of the auxiliary tank for introducing air into the auxiliary tank and for causing air to be forced from the auxiliary tank into the storage tank, the flow of water into the storage tank being maintained regardless of movement of the auxiliary tank.

3. In a water system, the combination with a pump and a pressure storage tank; of an auxiliary tank; a main passage connecting the pump and storage tank and extending through said auxiliary tank; and means controlled by movement of the auxiliary tank for introducing air into the auxiliary tank and for causing air to be forced from the auxiliary tank into the storage

tank, the flow of water into the storage tank being maintained regardless of the movement of the auxiliary tank.

4. In a water system, the combination with a pump and a pressure storage tank; of an auxiliary tank; a main passage connecting the pump and storage tank and extending through said auxiliary tank; and means including valve mechanism responsive to the movement of said auxiliary tank for closing the auxiliary tank to atmosphere and drain and opening it to pressure in the system for forcing air from the auxiliary tank to the storage tank.

5. In a water system, the combination with a pump and a pressure storage tank; of an auxiliary tank; a main passage connecting the pump and storage tank and extending through said auxiliary tank; and means including valve mechanism responsive to the movement of said auxiliary tank to one position for causing the auxiliary tank to be drained of water and filled with air and to another position for causing air to be forced by pressure in the system from the auxiliary tank to the storage tank.

6. In a water system, the combination with a pump and a pressure storage tank adapted to receive water from the pump and store same under pressure; of a main passage connecting the pump and storage tank; an auxiliary tank; valves carried by said auxiliary tank and included in the main passage, and having connections with atmosphere and drain, and adapted upon movement of the auxiliary tank in one direction to close the connections with atmosphere and drain.

7. In a water system, the combination with a pump and a pressure storage tank; of an auxiliary tank; a main passage connecting the pump and storage tank and extending through said auxiliary tank; a valve operable to one position to connect the auxiliary tank with atmosphere and to a second position to connect the auxiliary tank with the storage tank; a valve operable to one position to connect the auxiliary tank with a drain and to a second position to connect the auxiliary tank with the pressure in the system for forcing air from the auxiliary tank to the storage tank; said valves being operated simultaneously by movement of the auxiliary tank.

8. In a water system, the combination with a pump and a pressure storage tank; of an auxiliary tank; a main passage connecting the pump and storage tank and extending through the auxiliary tank; an air inlet provided with a check valve; a drain, a valve operable to one position to connect the auxiliary tank with the air inlet and to a second position to connect the auxiliary tank with the storage tank; a valve operable to one position to connect the auxiliary tank with the drain and to a second position

to connect the auxiliary tank with the pressure in the system for receiving air from the auxiliary tank; said valves being operated simultaneously by movement 5 of the auxiliary tank; and a duct from the air inlet to the drain located outside the auxiliary tank.

9. In an air charger for a water system including a pump and pressure storage 10 tank, the combination with an auxiliary tank having an air inlet and a drain; valve seats located above and below the auxiliary tank and adapted to be connected in a main water passage from the pump through the 15 auxiliary tank to the storage tank, the upper valve seat having ports connected respectively with the main passage, the auxiliary tank and the air inlet, the lower valve seat having ports connected respectively 20 with the main passage, the auxiliary tank and the drain; and valves controlled by the movement of the auxiliary tank for connecting the ports whereby the auxiliary tank can be drained and receive air or whereby 25 water can flow into the auxiliary tank to force air into the main passage.

10. In an air charger for a water system including a pump and pressure storage tank, the combination with an auxiliary tank having an air inlet and a drain; valve seats located on opposite sides of the auxiliary tank, one seat having ports connected with the air inlet and the storage tank, the other seat having ports connected with the 35 drain and the pump; a main passage from the pump to the storage tank including valves carried by the auxiliary tank and having ports adapted to cooperate with the above mentioned ports upon the movement 40 of auxiliary tank in one direction for draining the auxiliary tank and filling it with air and upon movement of the auxiliary tank in the opposite direction to cause water to flow into the auxiliary tank to force air 45 into the storage tank.

11. In an air charger for a water system including a pump and pressure storage tank, the combination with an auxiliary tank having an air inlet and a drain; valve 50 bodies including valve seats located above and below the auxiliary tank and adapted to be connected in a main water passage from the pump through the auxiliary tank to the storage tank, the upper valve body 55 having ports connected respectively with the main passage, the auxiliary tank and the air inlet, the lower valve body having ports connected respectively with the main passage, the auxiliary tank and the drain; valves controlled by the movement of the auxiliary tank for connecting the ports whereby the auxiliary tank can be drained and receive air or whereby 60 water can flow into the auxiliary tank to force air into the auxiliary tank to force air into the

main passage; and yielding means for holding the seats on said valves. 65

12. In an air charger for a water system including a pump and pressure storage tank, the combination with an auxiliary tank having an air inlet and a drain; valve bodies 70 including valve seats located above and below the auxiliary tank and adapted to be connected in a main water passage from the pump through the auxiliary tank to the storage tank, the upper valve body having ports connected respectively with the main passage, the auxiliary tank and the air inlet, the lower valve body having ports connected respectively with the main passage, the auxiliary tank and the drain; valves controlled by the movement of the auxiliary tank for connecting the ports whereby the auxiliary tank can be drained and receive air or whereby 75 water can flow into the auxiliary tank to force air into the main passage; and common means for maintaining the seats on the valves, said means serving also as stops to limit the movement of the auxiliary tank. 80

13. In an air charger for a water system including a pump and pressure storage tank, the combination with an auxiliary tank having an air inlet and a drain; valve bodies including valve seats located above and below the auxiliary tank and adapted to be connected in a main water passage from the pump through the auxiliary tank to the storage tank, the upper valve body having ports connected respectively with the main passage, the auxiliary tank and the air inlet, the lower valve body having ports connected respectively with the main passage, the auxiliary tank and the drain; valves controlled by the movement of the auxiliary tank for connecting the ports whereby the auxiliary tank can be drained and receive air or whereby water can flow into the auxiliary tank to force air into the main passage; supporting arms extending from opposite sides of said valve bodies; and bolts connecting the supporting arms on one valve body with those on the other valve body whereby to limit the travel of the auxiliary tank in either direction. 100 105 110

14. In a water system, the combination with a water pressure source and a main storage tank; of a main passage connecting the source and tank; a duct by-passing a portion of the main duct; means for introducing air into the by-pass duct and for causing air to be forced into the tank; means for opening and closing said by-pass duct to the main passage; and means providing a restriction in that portion of the main duct by-passed by said by-pass duct, said portion being unrestricted when the by-pass duct is closed and being restricted by said last means when the by-pass duct is open. 115 120 125

15. In a water system, the combination

with a water pressure source and a main storage tank; of a main passage connecting the source and tank; a duct by-passing a portion of the main duct; means for introducing air into the by-pass duct and for causing air to be forced from the by-pass into the tank; means providing a restriction in that portion of the main duct by-passed by the by-pass duct for restricting said portion when the by-pass duct is open to the main passage and means for rendering said restricting means operative when opening the by-pass duct.

16. In a water system, the combination with a pump and a pressure storage tank; of a main passage connecting the pump and storage tank; an auxiliary tank by-passing a portion of the main passage; means controlled by movement of the auxiliary tank for introducing air into the auxiliary tank and for causing air to be forced from the auxiliary tank into the storage tank; and means for restricting the flow of water through the by-passed portion of the main passage upon a certain movement of the auxiliary tank.

17. In a water system, the combination with a pump and a pressure storage tank; of a main passage connecting the pump and storage tank; an auxiliary tank by-passing a portion of the main passage; means controlled by movement of the auxiliary tank for introducing air into the auxiliary tank and for causing air to be forced from the auxiliary tank into the storage tank; and means controlled by the movement of the auxiliary tank for restricting the flow of water through the by-passed portion of the main passage.

18. In a water system, the combination with a pump and a pressure storage tank; of an auxiliary tank; a main passage connecting the pump and storage tank and extending through said auxiliary tank, said tank by-passing a portion of the main duct; means controlled by movement of the auxiliary tank for introducing air into the auxiliary tank and for causing air to be forced

from the auxiliary tank into the storage tank; and means for restricting the flow of water through the by-passed portion of the main passage upon a certain movement of the auxiliary tank.

19. In a water system, the combination with a pump and a pressure storage tank; of a main passage connecting the pump and storage tank; an auxiliary tank by-passing a portion of the main passage; means controlled by movement of the auxiliary tank for introducing air into the auxiliary tank and for causing air to be forced from the auxiliary tank into the storage tank; and means for restricting the flow of water through the by-passed portion of the main passage when air is being forced into the storage tank.

20. In a water system, the combination with a pump and a pressure storage tank; of a main passage connecting the pump and storage tank; an auxiliary tank by-passing a portion of the main passage; means controlled by movement of the auxiliary tank for introducing air into the auxiliary tank and for causing air to be forced from the auxiliary tank into the storage tank; and means controlled by the movement of the auxiliary tank for restricting the flow of water through the by-passed portion of the main passage when air is being forced into the storage tank.

21. In a water system, the combination with a water pressure source and a main storage tank; of means for connecting the source and tank; of a duct by-passing a portion of said means; of means for introducing air into the by-pass duct and for causing air to be forced into the tank; of means for opening and closing said by-pass duct to said first means; and means for restricting the flow of water in that portion of the first means by-pass by said by-pass duct, when the by-pass duct is open to the first means.

In testimony I hereto affix my signature.

CLARENCE WARNER.
